AUTOMATIC VOLUME CONTROL WITH
NOISE SUPPRESSOR

George L. Beers, Collingswood, N. J., assignor to
Radio Corporation of America, a corporation of
Delaware

Application March 15, 1933, Serial No. 660,885

15 Claims. (Cl. 250—20)

My present invention relates to radio receiver control systems, and more particularly to an automatic volume control arrangement utilizing a multi-vibrator oscillator as a noise suppressor.

5 It may be stated that it is one of the prime objects of my present invention to provide a suppressed background automatic volume control arrangement for a radio receiver wherein a multi-vibrator oscillator is employed in the suppressor circuit.

Another important object of the present invention is to provide in a radio receiver which includes an automatic volume control arrangement, a background noise suppressor device which comprises a multi-vibrator oscillator adapted to impair the operating efficiency of the detector or audio frequency amplifier of the receiver when the signal input to the receiver decreases below a predetermined intensity level.

20 The novel features which I believe to be characteristic of my invention are set forth in particularity in the appended claims, the invention itself, however, as to both its organization and method of operation will best be understood by 25 reference to the following description taken in connection with the drawings in which I have indicated diagrammatically two circuit organizations whereby my invention may be carried into effect.

30 In the drawings,

Fig. 1 shows a diagram of a receiver embodying the invention.

Fig. 2 shows a modification.

Referring now to the accompanying drawings, 35 which diagrammatically illustrates in Fig. 1 a radio receiver embodying the present invention, it will be noted that the receiver includes a source of signals 1, which is coupled, as at M, to the resonant input circuit of an amplifier tube S, preferably of the screen grid type, and that the output of the amplifier is coupled, as at M₁, to the resonant input circuit of the detector tube A. The audio frequency signal energy in the output circuit of the detector tube A is transmitted, 40 through a coupling M₂, to the input electrodes of an audio frequency amplifier tube A₁, and the amplified audio output of tube A₁ is then impressed, through a coupling M₃, upon any utilization means, such as another stage of audio frequency amplification and/or a reproducer of any desired type.

The receiver embodying the elements 1, S, A and A₁ may be included in a radio receiver of the tuned radio frequency type, or in one of the superheterodyne type. If the receiver is of the

tuned radio frequency type, then the resonant input circuits of the amplifier S and the detector A would have their condensers 2 and 3 variable, and rotors uni-controlled for tuning these circuits in the well known fashion. Of course, the 5 source of signals could then include one, or more, stages of radio frequency amplification, and would be uni-controlled in tuning with the input circuits of tubes S and A.

On the other hand, if the receiver is of the superheterodyne type, then the amplifier tube S designates an intermediate frequency amplifier tube, the condensers 2 and 3 being fixed and resonating the input circuits of the tubes to the operating intermediate frequency. As is well 15 known, the anode circuit of the amplifier S would then include the condenser 4 to resonate it to the same intermediate frequency. The detector A would then function as the second detector, and the source of signals 1 would comprise the usual 20 network preceding the intermediate frequency amplifier. Such a preceding network includes at least a stage of tuned radio frequency amplification ahead of a first detector, and a local oscillator coupled to the first detector, the output circuit of the first detector being coupled to the input electrodes of the amplifier S and providing the 25 intermediate frequency energy.

To maintain the signal input to the detector tube A substantially constant over a wide range 30 of signal input amplitude variations to the receiver, an automatic volume control arrangement is utilized. Such an arrangement utilizes the direct current component in the anode circuit of the detector A as a source of biasing potential for the amplifier S. Thus, the control electrode of the tube S is connected by a lead 5, designated 35 additionally by the symbol A. V. C. to point out that this lead is the automatic volume control path, to a desired point on the resistor 6. The biasing resistor 6 is connected between the anode of tube A and a point on the voltage divider, or potentiometer P, this point being positive with respect to the point on the divider P to which the 40 cathode of the tube A is connected. The control grid of the detector tube A is connected to a point on the divider P which is negative with respect to point 7 to which the cathode is connected.

The divider P may be employed to provide the 50 necessary energizing potentials for the electrodes of the amplifier tube S. Thus, the anode of tube S is connected through lead 8 to a point on the divider P which is positive with respect to the point 7' to which the anode of tube A is con- 55

nected; the cathode of the amplifier tube S is connected by a lead 9 to the point 8' on the divider. The operation of the automatic volume control arrangement described is believed too well known to warrant a lengthy explanation.

Briefly, when the amplified signal energy which is impressed upon the input circuit of the detector A increases above a desired level, then the grid of the tube S is biased negatively with respect to the cathode of tube S a sufficient amount to reduce the gain of the amplifier to such an extent that the energy impressed on the input of tube A is decreased to the aforementioned desired level. On the other hand, if the signal energy impressed upon the input circuit of the detector A decreases below this predetermined level, then the potential drop across the resistor 6 decreases sufficiently to bias the grid of tube S less negative with respect to the cathode, and this decrease in negative bias is sufficient to increase the gain of the amplifier tube S to such an extent that the signal energy delivered to the input circuit of the detector is maintained at the desired operating level.

Thus, the audio frequency signal energy impressed upon the audio frequency amplifier tube A₁ through the audio frequency transformer M₂, is maintained substantially constant regardless of variations in signal energy collected by the receiver. Manual control of the receiver output is provided by contact device 6' by which any portion of the audio frequency potential developed across resistor 6 may be impressed on the coupling device M₂.

The control electrode of the amplifier tube A₁ is maintained at a negative potential with respect to its cathode by connecting the grid through resistor F to a point on the bias resistor P₁ which is less positive than the point 10 to which the cathode of tube A₁ is connected. The grid of tube A₁ is connected to resistor F through a path which includes the lead 11, the secondary winding 12 of the transformer M₂, the lead 13, and the adjustable tap 13'. The lead 13 is designated "N. S." to point out that this is the background noise suppressor path, and the significance of this will be more fully described at a later point. Since resistors P and P₁ are connected in series, a single source of potential may be connected to the points marked - and + respectively. The bias of rectifier tube E is normally adjusted so that in the absence of a signal impressed on its grid the current flowing through resistor F is very small, and the bias on tube A₁ is then such that it amplifies in the normal manner.

In order to prevent the reproduction of undesirable background noise, when the receiver is tuned between stations, various devices may be employed. The drawings show one such device; such a device acts to bias the audio frequency amplifier to cut-off when the signal energy impressed upon the detector input decreases below the predetermined minimum signal level. The control of the amplifier A₁ is accomplished by means of the element F, and in this case is shown as a bias resistor, the potential drop across this resistor being regulated by means of the network including the amplifier tube B, the multi-vibrator oscillator comprising tubes C and D, and the rectifier tube E. This background noise suppressor network will now be described in detail.

The tube B is employed to amplify the potential drop across the resistor 6. The grid of tube B is connected to the anode of tube A through a direct current connection. The cathode of the tube B is connected to a point 16' on the divider

5 P which is positive with respect to the point 7', and the anode of tube B is directly connected to the grid of the multi-vibrator oscillator tube C. The point 16 on the divider P is positive with respect to the point 16' to which the cathode of tube B is connected, and this point 16 is connected to the anode and grid of tubes B and C respectively through a resistor 17, while the point 16 is connected through a resistor 17' to the grid of the other oscillator tube D. The point 18 on 10 divider P which is positive with respect to point 16, is connected to the anode of the tube C through a path which includes the coil 19 and the resistor 20 in series with each other, and this point 18 is similarly connected to the anode of oscillator 15 tube D through a resistor 21. Both cathodes of tubes C and D are connected to the point 19' which is more positive than point 16 and less positive than point 18.

The anode of oscillator tube D is connected 20 through a feedback condenser 22 to the grid of tube C, while the anode of the latter tube is connected to the grid of tube D through a feed-back condenser 22'. The output of the multi-vibrator oscillator is impressed upon the input circuit of 25 the rectifier tube E through a path which comprises a low or high pass filter with a sharp cut-off. The coil 19 in the plate circuit of tube C is coupled to the coil 19'', the latter coil being connected across the input terminals of the filter 30, 30 and the resistor 31, connected across the output terminals of filter 30, is connected in the grid circuit of rectifier tube E.

Specifically, the filter 30 is shown as a high 35 pass filter of a design well known to those skilled in the art. It will be noted that the grid of rectifier tube E is connected to a point on the divider P which is positive with respect to point 18; the cathode of tube E is connected to a still more positive point; while the anode of tube E is connected to the junction of P and P₁ through resistor F. Resistors P and P₁ may be constructed as a single resistor. By-pass condensers, 40, 40' and 40'' are employed respectively between the bias resistor F and the cathodes of tubes A₁ and E, and between the anode and cathode of the 45 detector tube A.

As stated heretofore the device which it is desired to control by the multi-vibrator oscillator network is the bias resistor F which is connected 50 in the plate circuit of rectifier tube E. This device F may be a relay if desired, and in that case could be used to operate a reproducer short-circuiting device, as described in my co-pending application Serial No. 475,474, filed August 15, 55 1930.

The frequency of a multi-vibrator oscillator, of the type including the tubes C and D, is controlled by the incoming signal. The filter 30 couples the oscillator to the rectifier, and by using a filter with a sharp cut-off characteristic a slight change in the frequency of the oscillator produced by the incoming signal will cause a large change in the oscillator voltage impressed on the grid of the rectifier E, and, therefore, a 60 large change in the direct current component flowing in the plate circuit of tube E. It is this direct current component change which is utilized to produce the background noise suppression function.

It has been experimentally determined that the 70 frequency of a multi-vibrator oscillator can be varied through several hundred kilocycles by varying the plate impedance of a tube. By the use of a suitable rectifier connected so that the 75

direct current component of the rectified voltage is used to supply bias for a second tube and thereby vary its plate impedance, the frequency of a multi-vibrator oscillator can be controlled 5 by the amplitude of a received signal. By connecting either a low or high pass filter ahead of another rectifier the plate current of this tube can be controlled by the amplitude of the incoming signal. If the filter ahead of this last mentioned rectifier has a sharp cut-off the change in 10 average plate current of the second rectifier, or control tube, will occur suddenly with a particular value of signal input. Since the steepness of the filter characteristic and the output of the 15 multi-vibrator oscillator governs the amount of control which can be obtained from such an arrangement, it is possible to obtain sufficient plate current change in the control tube E to vary the bias of either the audio frequency amplifier, or 20 the detector, so that they do not operate when signal energy below a predetermined level is being received.

Specifically considering the circuit elements of this arrangement, when a signal is impressed on 25 the grid of tube A, the average plate current of this tube is increased since it is biased near its cut-off point. The negative bias on the tube B is, therefore, increased due to the potential drop across the resistor 6 in the plate circuit of tube 30 A. The plate impedance of tube B, which shunts the resistor 17 in the grid circuit of tube C is, therefore, increased, thus increasing the effective impedance in the grid circuit of oscillator tube C, thereby lowering the frequency of the multi- 35 vibrator oscillator.

The multi-vibrator is a two stage resistance coupled amplifier in which the voltage developed in the output of the second tube is applied to the input of the first tube. Such an arrangement 40 will oscillate because each tube produces a phase shift of 180 degrees, causing the output of the second tube to supply an input voltage to the first tube that is in exactly the right phase to sustain oscillations. Since there is no resonant circuit, 45 the generated frequency is unstable, and the wave from some of the oscillating currents is very distorted. It is because of these properties that the multi-vibrator finds its usefulness. It is believed that the present description of the structure of 50 the multi-vibrator and its general method of operation is sufficient for the purposes of the present application. Reference is made to "Radio Engineering" by F. E. Terman, pages 273 to 276 inclusive for a more detailed theoretical explanation 55 of the operation of the multi-vibrator oscillator.

The filter 30 between the multi-vibrator and the rectifier E is of the high pass type and is designed to provide a high attenuation for the frequency at which the multi-vibrator oscillator 60 oscillates when a signal is being received. When the frequency of the oscillator is increased by tuning the receiver between stations, a large input voltage is impressed on the grid of tube E. The amplitude of this voltage depends entirely 65 upon the output of the oscillator and the cut-off characteristic of the high pass filter. When the large radio frequency voltage is impressed on the grid of tube E, it causes a large increase in the average plate current of tube E, since this tube is 70 normally biased near its cut-off point. This change in plate current is used to operate the device F, which, as has been stated heretofore, may be a relay or a bias resistor.

Since a tube capable of handling large plate 75 currents may be used for the tube E, and since

the multi-vibrator can be designed to provide a high voltage output, it will be possible to obtain a change in plate current of tube E of at least 10 milliamperes with a comparatively small radio frequency input. It is pointed out that the contact device 18' may be utilized as a manually operable device for controlling the signal level at which background noise suppression is to occur. 5

While the automatic volume control arrangement employed has been shown to comprise the utilization of the direct current component of the detector output, it is pointed out that the tube A need not be the detector tube of the receiver. For example, the tube may readily be a special automatic volume control tube, as described in an article by Beers and Carlson in the Proceedings of the Institute of Radio Engineers for March, 1929, pages 501-515. Also, the automatic volume control arrangement is not limited to the control of the gain of a single amplifier, but, in the case 15 of a superheterodyne receiver, may be used to control the gain of the radio frequency and intermediate frequency amplifier stages simultaneously. 20

In Fig. 2 is shown a modification of the invention wherein the plate potentials for tubes B, C, D, and E are all derived from the common source P₂. This combination of tubes in effect comprises a direct current amplifier. The operation is the same as in the case of Fig. 1, and need not be described again, since it is believed the diagrammatic showing will be sufficient. It is to be noted that in a conventional direct current amplifier the anodes of all the tubes cannot be supplied from a single source since the plate of one tube is directly connected to the grid of the following tube, etc. 25

While I have indicated and described a system for carrying my invention into effect, it will be apparent to one skilled in the art that my invention is by no means limited to the particular organization shown and described, but that many modifications may be made without departing from the scope of my invention as set forth in the appended claims. 30

What I claim is:

1. In combination, a radio frequency amplifier, a rectifier coupled thereto, a biasing path between an input electrode of said amplifier and the output circuit of said rectifier for automatically regulating the gain of said amplifier to maintain the 50 energy input to said rectifier substantially constant, an oscillator, a second rectifier, a filter network coupling the oscillator output to the rectifier input, means for coupling the output circuit of the first rectifier to said oscillator, and 55 means, responsive to variations in the output circuit of the second rectifier, for automatically rendering the reproduction of the audio modulations of the radio frequency energy impressed on said amplifier inefficient when the intensity 60 level of said impressed energy decreases below a desired minimum level.

2. In combination with a signal amplifier, a detector, an audio frequency amplifier, and means for automatically maintaining the signal amplitude at the detector input substantially uniform, a network for automatically regulating the transmission efficiency of said audio amplifier, said network comprising an oscillator having its input circuit coupled to the output circuit of said 65 detector, the oscillator having a frequency characteristic which is variable and dependent upon the current flow in the detector output circuit, a rectifier having its input circuit coupled to the 70 output circuit of said oscillator through a net- 75

- work having a predetermined frequency response characteristic, and a direct current connection between the output circuit of said rectifier and an input electrode of said audio amplifier.
5. In combination with a signal amplifier, a detector, an audio frequency amplifier, and means for automatically maintaining the signal amplitude at the detector input substantially uniform, a network for automatically regulating the transmission efficiency of said audio amplifier, said network comprising an oscillator having its input circuit coupled to the output circuit of said detector, the oscillator having a frequency characteristic which is variable and dependent upon the current flow in the detector output circuit, a rectifier having its input circuit coupled to the output circuit of said oscillator, and a direct current connection between the output circuit of said rectifier and an input electrode of said audio amplifier, and the coupling between said oscillator and said rectifier including a high pass filter with a sharp cut-off characteristic.
4. In combination with a signal amplifier, detector, and an audio frequency amplifier, a network for automatically regulating the transmission efficiency of said audio amplifier, said network comprising an oscillator having its input circuit coupled to the output circuit of said detector, a rectifier having its input circuit coupled to the output circuit of said oscillator through a network having a predetermined frequency response characteristic, and a direct current connection between the output circuit of said rectifier and an input electrode of said audio amplifier, said oscillator being of the multi-vibrator type and including a pair of resistance coupled tubes, the frequency of the oscillator varying inversely with the effective impedance in the input circuit of one of the oscillator tubes.
40. 5. In combination with a signal amplifier, a detector, an audio frequency amplifier, and means for automatically maintaining the signal amplitude at the detector input substantially uniform, a network for automatically regulating the transmission efficiency of said audio amplifier, said network comprising an oscillator having its input circuit coupled to the output circuit of said detector, the oscillator having a frequency characteristic which is variable and dependent upon the current flow in the detector output circuit, a rectifier having its input circuit coupled to the output circuit of said oscillator through a network having a predetermined frequency response characteristic, and a direct current connection between the output circuit of said rectifier and an input electrode of said audio amplifier, the coupling between said detector and the input of said oscillator including an amplifier tube for amplifying the potential drop across an impedance in the detector output circuit, the anode of said last named amplifier being connected to the grid of said oscillator tube.
6. In combination with a signal amplifier, detector, and an audio frequency amplifier, a network for automatically regulating the transmission efficiency of said audio amplifier, said network comprising an oscillator having its input circuit coupled to the output circuit of said detector, a rectifier having its input circuit coupled to the output circuit of said oscillator, and a direct current connection between the output circuit of said rectifier and an input electrode of said audio amplifier, and the coupling between said oscillator and said rectifier including a high pass filter with a sharp cut-off characteristic, said filter being de-
- signed to provide a high attenuation for the frequency at which the oscillator oscillates when no signal is being received.
7. In combination with a radio receiver including a radio frequency amplifier, a detector and an audio frequency utilization network, an arrangement for impairing the output of said audio frequency network when the signal input to the receiver decreases below a desired minimum level, said arrangement including a multi-vibrator oscillator having its input circuit coupled to the output circuit of the detector, the frequency of the oscillator being controlled by the incoming signal, a rectifier, a filter network coupling the output of said oscillator to the input of said rectifier, said filter having a characteristic such that a slight change in the frequency of said multi-vibrator produced by the incoming signal will cause a large change in the oscillator voltage on the grid of said rectifier and a large change in the flow of direct current in the anode circuit of said rectifier, and means in the rectifier anode circuit, responsive to the variations in the flow of direct current in the rectifier anode circuit, for impairing said audio frequency output.
8. In combination with a radio receiver including a radio frequency amplifier, a detector and an audio frequency utilization network, an arrangement for impairing the output of said audio frequency network when the signal input to the receiver decreases below a desired minimum level, said arrangement including a multi-vibrator oscillator having its input circuit coupled to the output circuit of the detector, the frequency of the oscillator being controlled by the incoming signal, a rectifier, a filter network coupling the output of said oscillator to the input of said rectifier, said filter having a characteristic such that a slight change in the frequency of said multi-vibrator produced by the incoming signal will cause a large change in the oscillator voltage on the grid of said rectifier and a large change in the flow of direct current in the anode circuit of said rectifier, and means in the rectifier anode circuit, responsive to the variations in the flow of direct current in the rectifier anode circuit, for impairing said audio frequency output.
9. In a radio receiving system, a signal amplifier, a source of local oscillations, signal responsive means for controlling the frequency of oscillations from said source, a rectifier, a biasing connection between the rectifier and said amplifier, and a frequency selective path interconnecting said oscillator and said rectifier.
10. In a radio receiver, an audio amplifier, a signal rectifier, means responsive to received signal amplitude variations for automatically maintaining the signal amplitude at the rectifier input substantially uniform, an oscillator having a variable frequency characteristic connected to said rectifier in such a manner as to be responsive in frequency to variations in signal carrier intensity fluctuations, means for rectifying the oscillator output energy, a network having a predetermined frequency response characteristic coupling said oscillator to said rectifying means, and means for utilizing rectified oscillator energy to regulate the efficiency of said amplifier.
11. In combination with an amplifier and a demodulator, an oscillator coupled to said demodulator to be responsive in frequency to variations in intensity of the signal carrier impressed

on said demodulator, means having a frequency response characteristic related to said oscillator frequency for deriving a uni-directional voltage from the oscillator output energy, means for regulating the amplifier gain with said voltage, and additional means, responsive to variations in the demodulated currents, to control the amplitude of the signal energy fed to said demodulator.

12. In an automatic volume control system for a radio receiver of the type which includes a signal amplifier, a signal demodulator, and a network for utilizing the demodulated signal energy, means responsive to variations in amplitude of received signal energy for automatically regulating the signal amplifier in a sense to maintain the signal energy input to the demodulator substantially constant in spite of said variations, an oscillator circuit having a characteristic such that the frequency of oscillations produced by it is dependent upon the direct current component of the demodulated signal energy, and means for automatically regulating the efficiency of said network in response to variations in the frequency of said oscillations.

13. In an automatic volume control system for a radio receiver of the type which includes a signal amplifier, a signal demodulator, and a network for utilizing the demodulated signal energy, means responsive to variations in amplitude of received signal energy for automatically regulating the signal amplifier in a sense to maintain the signal energy input to the demodulator substantially constant in spite of said variations, an oscillator circuit having a characteristic such that the frequency of oscillations produced by it is dependent upon the direct current component of the demodulated signal energy, and means for

automatically regulating the efficiency of said network in response to variations in the frequency of said oscillations, said last named means including a rectifier whose input is coupled to the output of said oscillator.

14. In a radio receiver of the type including a signal carrier amplifier, a demodulator, an audio frequency utilization network, and means responsive to signal amplitude variations for automatically varying the amplifier gain in a sense to maintain the signal carrier amplitude at the demodulator input substantially uniform, a background noise suppressor system which comprises an oscillator circuit for producing local oscillations of a definite frequency, a rectifier for deriving a direct current component from said oscillations, means for utilizing said component to control the transmission efficiency of said audio network, and means responsive to the direct current component of rectified signals for controlling the frequency of the output energy of said oscillator.

15. In an electrical wave transmission system including a wave transmission tube, a demodulator and a utilization network, means responsive to wave amplitude variations for automatically varying the wave transmission efficiency through said tube in a sense to maintain the wave amplitude substantially uniform at the demodulator input, an oscillation producing network constructed and arranged to be responsive in frequency to variations in wave amplitude, and frequency discriminating means, responsive to a predetermined change in frequency of said oscillation network, for regulating the transmission efficiency to said utilization network.

GEORGE L. BEERS.
